Patented Feb. 10, 1914.

UNITED STATES PATENT OFFICE.

HUBERT MEREDITH-JONES, OF NEW YORK, N. Y., ASSIGNOR TO COLUMBIA NUT AND BOLT COMPANY, INCORPORATED, OF BRIDGEPORT, CONNECTICUT, A CORPORATION OF NEW YORK.

STARTING MECHANISM.

1,086,683.

Specification of Letters Patent.

Patented Feb. 10, 1914.

Application filed January 13, 1913. Serial No. 741,645.

To all whom it may concern:

Be it known that I, HUBERT MEREDITH-JONES, a subject of the King of England, residing at New York city, county of New York, State of New York, have invented an Improvement in Starting Mechanism, of which the following is a specification.

This invention has for its object to provide a simple, easy working and thoroughly reliable mechanical starter which shall be adapted for general use and especially adapted for use upon explosive engines, as the mechanism is self-releasing in the event of a back-fire.

With this end in view, I have devised the novel mechanism of which the following description in connection with the accompanying drawing is a specification, reference characters being used to indicate the several parts.

Figure 1 is a longitudinal section of one form of the mechanism complete; Fig. 2 a transverse section on the line 2—2 in Fig. 1, looking in the direction of the arrows; Fig. 25 3 a detail sectional view on the line indicated by 3 in Fig. 2, looking in the direction of the arrow, and Fig. 4 is a detail sectional view illustrating a variation from the form in Fig. 1, which will probably be the preferred form.

10 denotes the engine shaft or an extension thereof, 11 a driven member rigidly secured thereto, 12 a driving member through which the shaft passes independently, 13 25 a disk which is secured to rotate with the shaft, as by means of a pin 14, but may slide longitudinally thereon, and 15 a nut on the end of the shaft by which the parts are retained in place. This nut is shown as provided with ratchet teeth adapted to receive a crank for cranking up at any time in lieu of using the starting mechanism. The driving member is actuated by means of driving rings 16 and 17 which are mounted to oscillate thereon and co-acting sets of rolls 18 and 19 which lie in recesses 20 in the periphery of the driving member. These recesses are slightly deeper at one end than at the other forming inclines 21 upon which the 30 rolls travel. The rolls are shown as provided with rounded ends, see Fig. 3, and may or may not contact lightly with each other and with the driven member and disk. The driving rings are provided respectively 50 with arms 22 and 23 which in use are moved

in the same direction simultaneously in any ordinary or preferred manner, as by means of links and a starting lever (not shown). The position of the rolls with relation to the driving rings and driving member will be clearly understood from Fig. 3, which see in connection with Fig. 2. When the arms are operated as described, one of the driving rings will be moved in one direction and the other ring in the opposite direction. The movement of the rings will be reversed on the return movement of the arms, so that by oscillating the arms one of the driving rings will always be acting to carry the driving member forward through the interposition of the rolls between the inner walls of the driving rings and the inclines. Each time a driving ring moves forward it will cause the corresponding rolls to travel up an incline and wedge between said ring and the driving member, carrying the driving member forward. While this movement is taking place the other driving ring will be moving backward, which will cause the rolls to drop backward into the relatively deep portions of the recesses. An instant later when the arm is reversed, the previously loose rolls will engage the driving member and the previously engaged rolls will drop back in the recesses. I have shown driving ring 16 as provided with a flange 24 which overlies a corresponding flange on the other ring and driving ring 17 as provided with a flange 25 which overlies the driven member, whereby dust is effectually excluded and the lubricant is retained.

26 and 27 denote front and rear dust caps carried respectively by driving rings 16 and 17. These dust caps which inclose the entire mechanism of the starter, may be secured to the driving rings in any suitable manner and are shown as provided with slots in their edges through which the arms extend.

The driven member and disk are retained in yielding engagement with the driving member by means of springs 28 and balls 29 which lie in holes 30 in the driving member. In Fig. 1, both the disk and the driven member are provided with sockets 31 which are engaged by balls. In Fig. 4, the driven member only is engaged by balls, the springs being longer and bearing directly on the disk or on interposed washers. Slightly cupped washers 32 are preferably interposed between the springs and the balls. These

- springs and balls insure that in starting, the forward movement of the driving member will be communicated to the driven member and the shaft to turn the engine.
- 5 The operation is as follows: To start the engine, (not shown) the operator swings the arms backward and forward, which, by means of the driving rings and the rolls, imparts forward movement to the driving member, which movement is, by means of the springs and balls, communicated to the driven member and the shaft. The instant the engine starts, the shaft, driven member and driving member will be caused to rotate 10 faster than the forward movement of the operative driving ring, the effect of which will be to disconnect the driving member therefrom, the rolls dropping back into the deep portions of the recesses and leaving the 15 starting mechanism wholly disconnected from the shaft. Should a back-fire of the engine take place, the effect will be to instantly and forcibly drive the shaft in the reverse direction, carrying with it the driven member and the disk. The driving member, however, is prevented from moving backward with the shaft owing to the forwardly driving pressure of the starting mechanism. The springs now yield and permit 20 the balls to pass from socket to socket in the driven member, as in Fig. 2, or in both driven member and disk, as in Fig. 1, until the power of the back-fire has exhausted itself, after which the springs and balls 25 will again lock the driving member to the driven member and the disk and the starting mechanism will again turn the shaft forward.
- Having thus described my invention I 30 claim:
1. Starting mechanism comprising a driving member having peripheral recesses with inclines, driving rings outside the driving member, rolls between the inclines and the 35 rings, a driven member, a disk and yielding means carried by the driving member and lying intermediate the driven member and the disk for yieldingly locking the driving member to the driven member.
- 50 2. Starting mechanism comprising a driven member, a disk, a driving member intermediate the driven member and the disk, alternately engaging driving means mounted upon the driving member and yielding means carried by the driving member and engaging the driven member and the disk for yieldingly locking the driving member to the driven member.
3. Starting mechanism comprising a driving member having peripheral recesses with inclines, driving rings outside the driving 55 members, rolls between the inclines and the
- rings, a disk, a driven member provided on its inner face with sockets, springs carried by the driving member and bearing on the 60 disk and balls controlled by the springs and adapted to engage the sockets to yieldingly lock the driving member to the driven member and permit backward movement of the driven member and disk independently of 65 the driving member should a backfire take place.
4. Starting mechanism comprising a driving member having transverse holes and peripheral recesses with inclines, driving rings 70 outside the driving member, rolls between the inclines and the rings, a driven member, a disk, and springs in the holes in the driving member and acting on the driven member and disk, substantially as described, for 75 the purpose specified.
5. Starting mechanism comprising a driven member, a driving member, and a disk, spring controlled means carried by the driving member and engaging the disk and 80 the driven member, whereby the driving member and the driven member are yieldingly locked together and alternately engaging driving means mounted upon the driving member.
6. Starting mechanism comprising a driving member having holes, a driven member, a disk, springs lying in the holes in the driving member and acting on the driven member and disk for yieldingly locking the 85 driving and driven members together, and alternately engaging driving means mounted on the driving member.
7. Starting mechanism comprising a shaft, a driving member loose thereon, a driven member rigidly secured thereto, a disk rotating with the shaft, springs carried by the driving member and acting upon the disk and driven member whereby the driving and driven members are yieldingly 90 locked together and alternately engaging driving means mounted upon the driving member.
8. Starting mechanism comprising a shaft, a driven member rigidly secured thereto, a disk adapted to rotate with the shaft, a loose driving member intermediate the driven member and the disk, means carried by the driving member and engaging the driven member and disk to yieldingly 95 lock said parts together and alternately engaging driving means mounted upon the driving member.

In testimony whereof I affix my signature in presence of two witnesses.

HUBERT MEREDITH-JONES.
